UNITED STATES PATENT OFFICE.

CLAUD E. ALLEN, OF CLEVELAND, OHIO, ASSIGNOR TO THE GUIDE MOTOR LAMP MANUFACTURING COMPANY, OF CLEVELAND, OHIO, A CORPORATION OF OHIO.

AUTOMOBILE LAMP.

Application filed January 10, 1921. Serial No. 436,106.

To all whom it may concern:

Be it known that I, CLAUD E. ALLEN, a citizen of the United States, residing at Cleveland, in the county of Cuyahoga and 5 State of Ohio, have invented a certain new and useful Improvement in Automobile Lamps, of which the following is a full, clear, and exact description, reference being had to the accompanying drawings.

10 This invention relates generally to lamps, and more particularly to one intended for use upon motor vehicles; and the object of the invention is to provide certain novel means for securing the reflector and glass in 15 the lamp body so as to avoid rattling.

Another object of the invention is to provide means for connecting these parts, independently, that is, means for connecting the reflector to the lamp body, separate 20 means for connecting the glass to the reflector; and still further independent means for securing all within the lamp body.

A still further object is to provide certain improvements in these parts whereby they 25 may be quickly and easily arranged within, or removed from, the lamp body; and a still further object is to provide a novel construction of ring fastening means so that access to the lamp for the purpose of cleaning 30 the same, or replenishing the incandescent bulbs can be quickly and easily accomplished.

With these various objects in view, the invention consists in certain novel features of 35 construction and also in the manner of combining or arranging said parts, all of which will be fully described hereinafter and pointed out in the claims.

In the drawings forming a part of this 40 specification Fig. 1 is a face view partly in section of a lamp embodying my invention; Fig. 2 is a vertical sectional view on the line 2—2 of Fig. 1; Fig. 3 is a detail view showing a portion of the lamp body; Fig. 4 is a 45 similar view of a portion of the reflector; Fig. 5 is a section on the line 5—5 of Fig. 1.

In carrying out my invention I employ a 50 sheet metal body 10 which may be given any general shape or configuration desired, and which is formed at its outer edge with an axially extending circumferential flange 11.

This sheet metal body portion may be provided with any suitable form of attaching bracket, and is also provided with socket connections for the main and the auxiliary 55 or dimmer incandescent lights.

The circumferential flange is provided with radial inwardly projecting lugs 12 preferably at equidistant points, said lugs being formed by punching the metal inwardly, and the circumferential flange is also formed, preferably at equidistant points with inwardly extending ears 13 which are also preferably formed by punching the metal inwardly, and in addition to the series 60 of ears, which are arranged at equidistant points, I also provide an additional pair of ears 14. The reflector engaging springs 15 are attached to the ears 13, which are arranged at equidistant points, said spring being in the form of an inwardly extending bow having the ends 15^a thereof turned to enter the inwardly projecting ears 13.

The reflector 16 is preferably of parabolic type and has a central opening to receive 75 the socket of the main light and is also provided at the proper place with a socket for receiving the auxiliary or dimmer light.

At the outer edge of the paraboloid, the reflector is formed with a circumferential 80 bead 17 which is substantially rectangular in cross section and projecting outwardly from this bead is the radially extending circumferential flange 18 and the flange with reflector is of such size as to fit snugly within the circumferential axial edge or flange portion 11 of the lamp body, and the circumferential flange 18 of the reflector contacts with and bears upon the springs 15 carried by the lamp body 10.

At definite points, the reflector flange is provided with notches 19 through which the inwardly projecting lugs 12 of the lamp body are adapted to pass, and then by giving the reflector a slight circumferential 95 movement, the flange thereof can be moved beneath the inwardly projecting lugs 12 thereby effecting the connection of the reflector through the lamp body. The bow springs 15 carried by the body being subjected to tension and acting as they do constantly upon the flange of the reflector hold 100

the reflector and body in locked relation and prevent rattling. In practice I prefer to upset the flange 18 at one point 20 adjacent one of the notches 19 in order to limit the 5 circumferential movement of the reflector flange beneath the radially inwardly projecting lugs.

The reflector flange is provided with a plurality, (preferably three) hooks or retaining 10 members 21 each one comprising a portion which extends axially outwardly, and a portion which extends radially inwardly, and the glass can be inserted from one side and brought into engagement with said 15 hooks or retaining members, and the periphery or edge of the glass will contact with the axially extending portions, while the radially extending portions overlap the edges of said glass and prevent any movement thereof. In practice, I prefer to arrange a cushion ring 22 of any suitable material upon the outer face of the bead of the reflector and against which the inner face 20 of the glass will contact.

25 In order to hold the glass in place upon the reflector, and also to effectively close the outer or front edge of the lamp body, I provide a sheet metal ring 23 which is flanged or channel shaped in cross section, the inwardly projecting edge thereof being adapted to contact with the outer face of the glass, and the outwardly projecting edge thereof being adapted to pass around and envelop the outer or forward edge of the body; and 30 in placing this ring upon the body it is first inserted over the outwardly projecting lugs 24 and then brought over the opposite side of the lamp body, and in order to secure the locking ring in engagement with the lamp body, 35 and the outwardly projecting lugs in particular, I employ a latch 25 within the lamp body and having its outer curved or hooked end 25^a working through an opening 26 produced in the circumferential edge of the body, the inner end 25^b of said latch, fulcruming against the interior of the lamp body, the intermediate portion of said latch having a screw 27 working therethrough, which screw passes through a small opening 40 produced in the lamp body in line with the opening 26 through which the outer end of the latch works; and the outer portion of this latch contacts with a bow spring 28 held in place by the additional pair of inwardly projecting ears 14 and as the screw is tightened 45 to project the outer curved or hooked end of the latch outwardly, the central portion of the spring is pressed inwardly and exerts a constant pressure upon the latch, so that 50 when the screw is loosened, the outer end of the said latch will be immediately forced inwardly inside the lamp body so that the adjacent portion of the ring 23 can be lifted clear of the edge of the lamp body, and after 55 that side of the ring has been cleared, a

slight movement of the ring will carry the opposite side away from, and out of engagement with, the outwardly projecting lugs 24, and the ring will be then entirely clear of the lamp body.

70 The glass, however will remain in its proper position upon the front of the reflector, being held there by the hooks or retaining members 21.

75 By removing the ring and glass, access can be had to the lamp for the purpose of cleaning the reflector or replenishing the lights, and in case it is desired to remove the reflector itself, it is only necessary to first remove the main incandescent light, and then give the reflector a slight rotary movement, so as to bring the notched edges thereof 19 opposite the inwardly projecting lugs 12 and then the reflector as a whole can be lifted 80 from the lamp body.

85 The bow springs 15 carried by the lamp body prevent any movement taking place between the body and reflector and thereby eliminate rattle at this point, and the ring securely holds the glass in place upon the cushion ring of the reflector and consequently all rattle at these points is eliminated.

90 The various features of construction herein set forth lend themselves readily to reduce the cost of production in providing a highly 95 efficient and easily manipulated headlight lamp for motor vehicles.

95 Instead of employing an ordinary screw, to operate the latch, I may provide said screw with a milled head; or a wing nut may 100 be provided, or any other suitable bolt or latch actuating device may be employed; and it will also be understood that certain changes or modifications may be made with 105 reference to the other details of construction within the scope of the appended claims.

Having thus described my invention, what I claim is:

110 1. A lamp body having an axial circumferential edge, a reflector having a radial flange at its outer edge, means carried by the lamp body for limiting the inward movement of the reflector, and springs attached 115 to the axial edge of the lamp body and adapted to engage the flange of the reflector, a glass held in contact with said reflector, a ring engaging the outer face of the glass and the exterior of the lamp body, and a latch arranged upon the interior of the lamp body 120 at one side, and a screw working through the lamp body and adapted to actuate said latch to hold the ring in place.

125 2. In a lamp, the combination with a body having outwardly extending portions adjacent the forward edge at one side thereof, said body also having inwardly projecting lugs, of springs carried by said body, and a latch also carried by said body having its outer end working through an opening in 130 said body adjacent the forward edge there-

of, a reflector arranged within the body and resting upon the springs carried by said body, the outer edge of said reflector engaging the inwardly projecting lugs, a glass arranged upon the front of said reflector, means carried by said reflector to hold said glass in position and a ring adapted to envelop the outer edge of the lamp body and the outwardly projecting portions together with means for actuating said latch to engage said ring. In testimony whereof, I hereunto affix my signature.

CLAUD E. ALLEN.
